UNITED STATES PATENT OFFICE.

HOLLIS LINTON MORRILL, OF MONTICELLO, MAINE.

VENTILATOR.

No. 823,360

Specification of Letters Patent.

Patented June 12, 1906.

Application filed August 21, 1905. Serial No. 275,032.

To all whom it may concern:

Be it known that I, HOLLIS LINTON MORRILL, a citizen of the United States, and a resident of Monticello, in the county of Aroostook and State of Maine, have made certain new and useful Improvements in Ventilators, of which the following is a specification.

My invention is an improvement in ventilators of the type adapted to be inserted in a window; and it consists in certain novel constructions and combinations of parts herein-after described and claimed.

In the drawings, Figure 1 is a plan view of my improved ventilator in place. Fig. 2 is a section on the line 2 2 of Fig. 1, and Fig. 3 is a section on the line 3 3 of Fig. 1.

In the present application of my invention I provide a triangular plate A, one of whose angles *a* is a right angle, and a part of the plate is cut away, as at *a'*, to form a triangular opening having an area less than half the area of the plate, the said triangular opening having angles similar to the angles of the triangular plate.

25 A flange *a'* is arranged upon the side of the triangular plate opposite to the right angle, the outer edge of the flange being shaped upon the arc of a circle having a radius somewhat greater than the altitude of the triangular plate. The depth of the flange is equal to the thickness of the window-pane, so that when the ventilator is in place the surface of the plate and the surface of the window-pane will be flush with each other.

30 A triangular cover B is pivoted by its apex to the apex of the triangular plate by means of the screw *b*, the cover being of an area sufficient to cover the triangular opening when in one position.

40 At each of the lower angles of the triangular plate are arranged blocks *c*, to which are secured a segmental guard C, the guard being longitudinally slotted, as at *c'*, for a purpose to be hereinafter described. The segmental guard overlaps the free end of the triangular plate, the said guard being formed upon the arc of a circle whose radius is equal to that of the altitude of the triangular cover. A latch D is provided for securing the cover in its adjusted position, the latch comprising a screw *d*, traversing the longitudinal slot and engaging the cover, a cam-shaped arm *d'* being ar-

ranged above the guard and a knob *d''*, rigid with the arm, being provided for convenience in manipulating the same. When the arm is turned so that the cam-shaped portion engages the guard, the cover is locked thereto.

55 In practical use my improved ventilator is inserted in the corner of a window-pane, a triangular section of glass being removed for the reception thereof. The edge of the glass rests against the flange and is maintained in contact therewith by means of the cover on the opposite side. By manipulating the latch on the cover the same may be adjusted 60 to give any desired degree of opening, or the opening may be entirely closed.

Having thus described my invention, what I claim as new, and desire to secure by Letters Patent, is—

70 1. A ventilator adapted to be fitted in the corner of a window-pane and comprising a triangular plate, one of whose angles is a right angle, the plate having a triangular opening therethrough of less area than one-half the area of the plate, a flange on the side of the plate opposite the right angle, a substantially triangular plate pivoted by its apex to the apex of the first plate and adapted to close the opening, a slotted guard for 80 the free end of the second plate, and secured to the first plate at either end, and a latch for the second plate comprising a screw traversing the slot in the guard and engaging said second plate, a cam-shaped arm on the screw 85 for engaging the guard and a knob above the arm.

2. A ventilator comprising a triangular plate adapted to be fitted in the corner of a window-pane, the plate being provided with 90 a triangular opening at one side thereof, a flange on the plate for engaging the edge of the window-pane, a cover for the opening pivoted to the plate, a guard for limiting the motion of the cover, and a latch for the cover 95 comprising a screw connected with the cover, and having a cam-shaped arm for engaging the guard.

3. A ventilator comprising a triangular plate having a triangular opening of less extent than half the area of the plate and adapted to be fitted in the corner of a window-pane, a cover for the opening pivoted to the plate, a guard for limiting the motion of the

cover, a latch for securing the cover in its adjusted position, and means on the plate for engaging the edge of the window-pane.

4. A ventilator, comprising a substantially triangular plate, adapted to be fitted in the corner of a window-pane and having an opening therethrough, a cover pivoted to the plate, a guard for limiting the movement of

the cover, and a latch on the cover for engaging the guard to secure the cover in its position of adjustment.
